United States Patent Office

Des. 213,006
Patented Dec. 24, 1968

213,006

HEARING AID

Ronald R. Giller, Danbury, Conn., assignor to
Distograph Products Inc., Danbury, Conn., a
corporation of Delaware

Filed Mar. 29, 1968, Ser. No. 11,214

Term of patent 14 years

(Cl. D26—14)

FIG. 1

FIG. 2

FIG. 3

FIG. 4

FIG. 5

FIG. 6

FIGURE 1 is a perspective view of the hearing aid of the present invention.

FIGURE 2 is a top plan view thereof; the undisclosed bottom side is a mirror image of the top shown;

FIGURE 3 is a left side elevational view of the hearing aid of FIGURE 1.

FIGURE 4 is a front elevational view of the hearing aid of FIGURE 1.

FIGURE 5 is a right elevational view of the hearing aid of FIGURE 1.

FIGURE 6 is a rear elevational view of the hearing aid of FIGURE 1.

I claim:

The ornamental design for a hearing aid, substantially as shown and described.
